UNITED STATES PATENT OFFICE.

GEORGE J. PILGER, OF SCRANTON, PENNSYLVANIA.

AIR-BRAKE GASKET-REPLACING TOOL.

No. 823,189.

Specification of Letters Patent.

Patented June 12, 1906.

Application filed September 18, 1905. Serial No. 278,886.

To all whom it may concern:

Be it known that I, GEORGE J. PILGER, a citizen of the United States, residing at Scranton, in the county of Lackawanna and State of Pennsylvania, have invented certain new and useful Improvements in Air-Brake Gasket-Replacing Tools; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to tools for facilitating repairs to leaky air-brake hose-couplings.

It embodies new and useful improvements in the form of tool covered by my Patent No. 787,857, dated April 18, 1905.

20 Its object is to provide a compact appliance specially adapted to remove old and worn-out rubber packing-gaskets between air-brake couplings, clean out the gasket-groove, and place the new gasket in position

25 with the least delay possible and with the least inconvenience to the train hands. This object I attain by means of the device illustrated in the accompanying drawings, where-

30 Figure 1 represents a general view of my improved gasket-replacing tool. Fig. 2 represents a view of one member of the familiar form of air-brake hose-coupling, partly broken away, with the cleaner end of the said tool inserted in the mouth of the coupling for the purpose of scraping out the gasket-groove; and Fig. 3 represents the coupling with the replacer end of the tool inserted for the purpose of forcing the new gasket home in said

40 groove.

The same letters refer to the same parts where they occur in more than one view.

Referring now to Fig. 1, A represents the body of the tool, which is preferably formed of a piece of sheet-steel in the general shape shown. At what I shall call the "front" end of the tool the metal is cut away, so as to leave the irregular hook-shaped projection or prong B, the end of which is turned up somewhat and brought to a dull cutting edge. C is an elbow-shaped jaw pivoted at D to one face of the body-piece A, and E is a similar jaw pivoted at the same relative point on the other face of the said piece. F F and G G are teeth formed on the free end of the jaws C and E. At H there is a wide slot cut out of

the body-piece A, within which play the lugs I K, attached to the jaws C and E, respectively, when the jaws move back and forth. L is a spring pressing against the jaw C in such way as to keep said jaw normally closed. A like spring on the other face of the tool (not shown) keeps the other jaw E closed in the same way. At the back end of the tool the body-piece A is cut away, as shown. M M are rollers shaped with a flange N at their forward end. These rollers are mounted on the long pivots O O and seated against the springs P P, so as to yield and slide along said pivots under pressure.

70 Passing to Fig. 2, Q represents one member of an air-brake hose-coupling. Part of the knuckle is broken away in order to show in section the groove R, just within the mouth of the coupling, designed for the rubber packing-gasket and to illustrate the position of the gasket-replacing tool when the front end thereof is being used.

75 Fig. 3 shows a similar view of the coupling with the back end of the tool inserted in the mouth thereof, S being the rubber packing-gasket in section.

The various parts of my invention being constructed and arranged as described, its purpose and mode of operation are as follows: 80 With the prong B the old gasket is quickly flipped out. The front end of the tool is then advanced into the mouth of the coupling, as shown in Fig. 2, until the teeth F F G G of the movable jaws C E are pressed into place, 85 the teeth G G entering the gasket-groove and F F pressing against the face of the coupling. A few turns of the tool back and forth now suffices to clean out the groove, and the fact that the jaws C E are movable enables the 90 tool to adjust itself to couplings varying somewhat in size. The new gasket is now slipped into the groove, and the back end of the tool is applied to the mouth of the coupling, as shown in Fig. 3. By pressing on the 100 tool and revolving it the spring-seated rollers M M press against the gasket, while the flanges N N force the gasket firmly and evenly home.

Having thus described my invention, what 105 I claim, and desire to secure by Letters Patent, is—

1. A tool for replacing worn-out gaskets in air-brake hose-couplings, consisting of a body-piece, a pair of coöperating, oppositely-placed jaws pivoted thereto at the front end and adapted to enter the gasket-groove, and

2
at the back end a pair of rollers adapted to force the gasket into place.

2. A tool for replacing worn-out gaskets in air-brake hose-couplings, consisting of a flat body-piece A, the elbow-shaped coöperating jaws C, E pivoted on opposite faces thereof at its front end, said jaws being provided at their free ends with the teeth G, adapted to enter the gasket-groove, and the teeth F, 10 adapted to scrape the face of the coupling, and at the back end of said body-piece A the

coöperating rollers M, M mounted on the pivots O and seated against the springs P, said rollers being shaped with the flange N at their front end, adapted to press the gasket home, 15 substantially as shown and described.

In testimony whereof I affix my signature in presence of two witnesses.

GEORGE J. PILGER.
